UNITED STATES PATENT OFFICE.

ALBERT OWEN HOLTOM, OF NEW YORK, N. Y.

DESIGN FOR A RADIATOR.

53,444.

Specification for Design.

Patented June 17, 1919.

Application filed October 26, 1917. Serial No. 198,734. Term of patent 14 years.

To all whom it may concern:

Be it known that I, ALBERT O. HOLTOM, a subject of the King of England, residing at New York city, in the county of New York and State of New York, have invented a new, original, and ornamental Design for Radiators, as shown in the accompanying drawing and described in the following specification.

Referring to the drawings:

Figure 1 is a front elevation of a radiator showing this design, and

Copies of this patent may be obtained for five cents each, by addressing the "Commissioner of Patents, Washington, D. C."

Fig. 2 is a side elevation of the upper portion thereof.

I claim:

The ornamental design for a radiator as shown.

ALBERT OWEN HOLTOM.

Witnesses:

HOMER METZGAR,
ELLEN LAMA.
